UNITED STATES PATENT OFFICE.

AFFONSO DE FIGANIÈRE, OF NORRISTOWN, PENNSYLVANIA.

DESULFURIZING APPARATUS.

SPECIFICATION forming part of Letters Patent No. 612,717, dated October 18, 1898.

Application filed April 29, 1898. Serial No. 679,242. (No model.)

To all whom it may concern:

Be it known that I, AFFONSO DE FIGANIÈRE, a citizen of the United States, residing at Norristown, in the county of Montgomery and State of Pennsylvania, have invented certain new and useful Improvements in Desulfurizing Apparatus; and I do hereby declare the following to be a full, clear, and exact description of the invention, such as will enable others skilled in the art to which it appertains to make and use the same.

This invention relates to the art of desulfurizing ores, and it is especially intended for use in connection with refractory auriferous ores.

The object of the invention is to provide an apparatus for economically and efficiently oxidizing the oxidizable constituents of refractory auriferous ores.

The invention involves an apparatus wherein atmospheric air is raised to a proper degree of heat and passed through the ore-body in such regulated volume as will supply oxygen sufficient to produce oxidation; or such slow combustion as will avoid heating the mass to such a degree as will melt the contained iron and thereby produce a matte.

The invention consists in the combination of a furnace for heating air, an ore-chamber through which the air is conducted, and means for exhausting or drawing heated air through the body of ore.

It also consists in other combinations of instrumentalities associated with the elements of the principal combination, which will be hereinafter described, and specifically pointed out in the claims.

In the drawings forming a part of this specification I have illustrated a convenient form of my invention, in which—

Figure 1 is a side elevation. Fig. 2 is a central longitudinal section; Fig. 3, a transverse section of my improved apparatus. Fig. 4 is a broken plan showing the application of a blower or other means for exhausting air from the ore-chamber.

As this apparatus is intended for use in localities remote or where transportation is difficult and inaccessible I have organized the apparatus so that it may be taken in sections

or pieces and in that way transported upon pack-animals, so that it may be set up and used near mines located in the wilderness.

1 represents a grate; 2, a bridge-wall of an ordinary or convenient form of furnace. This furnace will communicate with a suitable stack or flue for carrying off the products of combustion. The walls of the fire-chamber or furnace are made up of metallic sections bolted together, as clearly shown in the drawings. The inside of this chamber is lined with asbestos or other refractory substance 3 to protect the iron from excessive heat and injurious action of the products of combustion. Outside or at the sides of the furnace or combustion-chamber is a jacket or housing 4, providing a chamber or passage between itself and the outer walls of the furnace. Leading to this chamber or passage are flues or conduits 5, provided with gates 6 or dampers. Above the arch of the furnace-chamber is provided a chamber 7, which I call the "air-heating" chamber. This chamber is filled with blocks of pumice, broken fire-brick, or other like non-oxidizable porous substance, the top of the chamber being slotted or provided with perforations 8 for the free passage of air through and out of said chamber. Above the air-heating chamber is provided an ore-chamber 9, into which pulverized ore is fed through covers 10, the chamber being intended to be filled up to about the line represented in the drawings, and the top of this chamber is also provided, as illustrated, with perforations 11, through which the air 85 may be drawn by means of a suitable exhaust apparatus 12, as shown in Fig. 4, there being provided above the ore-chamber domes or spaces 13, with which communicate exhaust passages or flues 14, leading together and discharging through a passage 15 to the blower and thence to the atmosphere. The ore-chamber is provided with a series of ports closed by doors 16 for the convenient withdrawal of the ore from the chamber after it has been 95 treated to oxidize the oxidizable constituents of the ore. These doors are conveniently held in place by means of keepers consisting of eccentric levers 17, adapted to be rocked on their pivots, so as to release or loosen the door 100

for removal and insertion and to be thrown into operative position to clamp the doors in firm contact with the boundaries or edges of the ports. In operation, the chamber 7 being 5 filled with blocks of pumice or the like and the ore-chamber filled with pulverized ore, the doors and covers being luted to render the ore-chamber air-tight, fire is started on the grate and the pumice raised to a high degree 10 of heat, after which the dampers or gates 6 are raised or opened and the blower started in operation. The gates are adjusted to regulate the volume of air admitted through the passages 5, and as it passes through the mass 15 of pumice the air becomes heated to from 400° Fahrenheit to 600° Fahrenheit, more or less, whereupon the sulfur and other volatile metals are oxidized and carried off in fumes by the blower to the atmosphere or to any washing or condensing attachment, as may be desired. The volume of air being heated and introduced into the body of ore operates to oxidize its oxidizable constituents by a process of what I term "slow" combustion—that 25 is, a combustion so regulated as to prevent the mass of ore from becoming heated to such a degree as to melt or fuse the contained iron in such a way as to produce a matte, my object being to oxidize the ore without producing matte. The volume of air admitted must be regulated to correspond with the character of the ore, so as to be sure to avoid such rapid combustion as to develop too great a heat in the body of ore. This can be done by an experienced operator without difficulty or may 30 be determined by the use of pyrometers or suitable heat-indicators arranged within different parts of the ore-chamber, so that the

operator may observe and know just the degree of heat being generated in said chamber. 40

Having described my invention, what I claim as new, and desire to secure by Letters Patent, is—

1. In a desulfurizing apparatus, the combination of a combustion-chamber, an air-heating chamber filled with blocks of refractory substance arranged above the combustion-chamber and provided with a slotted or perforated roof portion, an ore-chamber arranged above the air-chamber provided with a perforated or slotted roof or top portion, a space or dome above the top of the ore-chamber, means for exhausting from the dome, and means for regulating the admission of air to the air-heating chamber, substantially as described. 45

2. In apparatus for desulfurizing ores, the combination of a combustion-chamber, an air-heating chamber arranged above the combustion-chamber having a perforated or slotted 60 roof and filled with refractory material, an ore-chamber arranged above the air-heating chamber, provided with a perforated or slotted roof, a dome or space on opposite sides of the roof portion, means for exhausting gases 65 from the domes, air-ducts leading from the atmosphere to the air-heating chamber, and gates or dampers for regulating the volume of air admitted to said chamber, substantially as described. 70

In testimony whereof I affix my signature in presence of two witnesses.

AFONSO DE FIGANIÈRE.
